[57] CLAIM

The ornamental design for an oral feeding utensil, as shown and described.

DESCRIPTION

FIG. 1 is a front perspective view of an oral feeding utensil showing my new design;

FIG. 2 is a right side elevational view of the oral feeding utensil, the left side elevational view being a mirror image thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a perspective view of a second embodiment of the oral feeding utensil shown in FIG. 1.

FIG. 2

FIG. 1

FIG. 4

FIG. 3

FIG. 5

FIG. 6

FIG. 7
